UNITED STATES PATENT OFFICE.

JAMES W. PATTERSON, OF BURLINGTON, IOWA.

DOSE-MEASURING BOTTLE-STOPPER ATTACHMENT.

SPECIFICATION forming part of Letters Patent No. 730,044, dated June 2, 1903.

Application filed January 9, 1903. Serial No. 138,437. (No model.)

To all whom it may concern:

Be it known that I, JAMES W. PATTERSON, a citizen of the United States, residing at Burlington, in the county of Des Moines and State of Iowa, have invented certain new and useful Improvements in Dose-Measuring Bottle-Stopper Attachments; and I do hereby declare the following to be a full, clear, and exact description of the invention, such as will enable others skilled in the art to which it appertains to make and use the same.

My invention relates to certain improvements in dose-measuring bottle-stopper attachments. It has for its object to provide a simple, efficient, and reliable bottle-stopper attachment which may be used for measuring proper doses from the contents of a bottle and also as a means for taking the doses. Other objects of the invention are hereinafter set forth.

The nature and characteristic features of my invention will be fully understood from the following description, taken in connection with the following drawings, forming part thereof, and in which—

Figure 1 is a side elevation of my improved bottle-stopper attachment applied to an ordinary stopper. Fig. 2 is an end view looking in the open end of the receptacle, said receptacle being applied to an ordinary stopper. Fig. 3 is a side elevation showing the receptacle removed from the stopper proper. Fig. 4 is a side elevation, in central section, of my bottle-stopper attachment applied to a bottle; and Fig. 5 shows a modification of my invention in which a vent is provided through the stopper.

Referring more particularly to the drawings, 1 is a receptacle, shown as of generally cylindrical form, being, preferably, open at each end, at one end, however, having its walls converging inwardly to form a tapering mouth 2. Said tubular receptacle is preferably made of glass and is removably attached to an ordinary cork, rubber, or other stopper, the only requisite being that it must be capable of making an air-tight connection at its under side. To prevent said receptacle from coming in contact with the bottle-neck having vertical walls, the cork is somewhat re-

duced in size at its inner end for the reception of said tubular receptacle 1. It will be understood that this tubular receptacle can be made in various sizes to hold any stated amount and can be adapted to any ordinary stopper.

In using my dose-measuring stopper attachment, it having been attached in the above manner to an ordinary stopper and said stopper fixed securely into the bottle, said bottle is inverted to cause a sufficient quantity of the liquid in the bottle to flow into and to fill the tubular receptacle 1. Upon returning the bottle to its upright position the liquid in said tubular receptacle will be retained therein, either by capillary attraction or by reason of the converging walls at the lower end thereof. When removed from the bottle, the tongue or some other surface, preferably a moist surface, applied to the opening will instantly empty the receptacle of its contents.

It will be readily seen that I may attach my tubular receptacle to the cork or other stopper provided with an upward vent therethrough, in which case the finger or thumb may be placed over its outer opening while the bottle is inverted to fill the tubular receptacle and when filled and removed from the bottle the contents may be discharged by simply removing the finger or other surface from the vent.

It is obvious that, if it is desired, the cork and the receptacle may be made of glass or any other preferred material.

Having thus described my invention, what I claim as new, and desire to secure by Letters Patent, is—

The combination with a bottle-stopper reduced at its inner end of a stopper attachment comprising a tubular receptacle open at each end and adapted at one end to receive said reduced inner end of said stopper, the walls of said receptacle converging at its other end to retain a liquid in said receptacle.

In testimony whereof I affix my signature in presence of two witnesses.

JAMES W. PATTERSON.
